Primary Examiner — Ian Simmons*Assistant Examiner* — Shannon Morgan(74) *Attorney, Agent, or Firm* — Millen, White, Zelano & Branigan, P.C.(57) **CLAIM**

The ornamental design for a measuring jug, as shown and described.

DESCRIPTION

FIG. 1 is a perspective view of the measuring jug showing my new design.

FIG. 2 is a left side elevational view thereof;

FIG. 3 is a right side elevational view thereof;

FIG. 4 is a bottom plan view thereof;

FIG. 5 is a top plan view thereof;

FIG. 6 is a front elevational view thereof; and,

FIG. 7 is a rear elevational view thereof.

The broken lines shown in FIGS. 1-7 represent portions of the measuring jug that form no part of the claimed design.
